Primary Examiner — Terry Wallace(74) *Attorney, Agent, or Firm* — Patterson Thuente Pedersen, P.A.(57) **CLAIM**

I claim the ornamental design for kitchen utensil, as shown and described.

DESCRIPTION

FIG. 1 is a front view of a kitchen utensil showing my new design.

FIG. 2 is a rear view of the kitchen utensil depicted in FIG. 1.

FIG. 3 is a bottom view of the kitchen utensil depicted in FIG. 1.

FIG. 4 is a top view of the kitchen utensil depicted in FIG. 1.

FIG. 5 is a right side view of the kitchen utensil depicted in FIG. 1.

FIG. 6 is a perspective view of the kitchen utensil depicted in FIG. 1; and,

FIG. 7 is a perspective view of the kitchen utensil depicted in FIG. 1 shown in its environmental setting.

Items shown in broken lines are for illustrative purposes only and form no part of the claimed invention. A left side view is omitted as it would be a mirror image of the right side view illustrated in FIG. 5.
